US00D485310S

(12) **United States Design Patent** (10) Patent No.: **US D485,310 S**
 Bartholomew et al. (45) Date of Patent: ** Jan. 13, 2004

(54) **COSMETIC DISPENSER**

(75) Inventors: **Julie R. Bartholomew**, Birmingham, MI (US); **Richard T. Jobe**, Dayton, OH (US); **Thomas C. Bodiker, II**, Englewood, OH (US)

(73) Assignee: **IMX Labs, Inc.**, Birmingham, MI (US)

(**) Term: **14 Years**

(21) Appl. No.: **29/157,727**

(22) Filed: **Mar. 22, 2002**

(51) LOC (7) Cl. **20-01**

(52) U.S. Cl. **D20/4**

(57) **CLAIM**

The ornamental design for a cosmetic dispenser, as shown and described.

DESCRIPTION

FIG. 1 is a perspective view illustrating a cosmetic dispenser of the present invention;

FIG. 2 is a front elevational view thereof;

FIG. 3 is a top view thereof;

FIG. 4 is a bottom view thereof;

FIG. 5 is a side view thereof; and,

FIG. 6 is another side view thereof.

The broken lines in the drawings depict environmental structure, which forms no part of the claimed design.
